UNITED STATES PATENT OFFICE.

JOHN PIUS HEUER, OF PITTSBURG, PENNSYLVANIA.

RAIL-JOINT.

937,600.

Specification of Letters Patent. Patented Oct. 19, 1909.

Application filed May 11, 1909. Serial No. 495,208.

To all whom it may concern:

Be it known that I, JOHN PIUS HEUER, a citizen of the United States of America, residing at Pittsburgh, in the county of Allegheny and State of Pennsylvania, have invented certain new and useful Improvements in Rail-Joints, of which the following is a specification, reference being had therein to the accompanying drawing.

10 This invention relates to rail joints, and more particularly to certain new and useful improvements in connection with my rail joint shown in Patent No. 731,181 granted to me June 16, 1903.

15 The primary object of the present invention is to provide a stronger and more durable rail joint than that disclosed in the above mentioned patent.

Another object of this invention is to 20 combine strength, stiffness and simplicity in construction in providing a rail joint that allows expansion and contraction of the rails without displacing any of the elements thereof.

25 These and such other objects as may hereinafter appear are attained by a joint that will be presently considered in detail, and then specifically pointed out in the appended claims, and reference will now be had to the 30 drawing forming part of this specification, wherein there is illustrated a preferred embodiment of the invention, but it is to be understood that the structural elements thereof can be varied or changed, as to the 35 shape, proportion and manner of assemblage without departing from the spirit and scope of the invention.

In the drawings, Figure 1 is a side elevation of the joint as applied to rails, Fig. 2 is 40 a plan of the same, Fig. 3 is a longitudinal sectional view of a portion of the joint, Fig. 4 is a cross sectional view of the same, and Fig. 5 is a perspective view of a detached splice bar.

45 In the drawings, 1 designates the heads, 2 the webs, and 3 the base flanges of rails adapted to confront one another and be supported through the medium of ties or sleepers 4. The webs 2 of the rails have ordinary 50 bolt openings 5 at the ends thereof, and detachably mounted in these openings are pins 6.

55 7 designates side plates provided with elongated openings 8 to receive the ends of the pins 6, the combined thickness of the plate 7 and the webs 2 corresponding to the

lengths of the pins 6, whereby the ends of the pins 6 will not protrude beyond the outer sides of the plates 7. The object of the plates 7 is to connect the rails and prevent 60 longitudinal displacement of one rail with relation to the other, but at the same time allow expansion and contraction of the rails.

9 designates splice bars having integral tie plates 10. The tie plates 10 are adapted 65 to rest upon the ties 4 and support the base flanges 3 of the rails, thereby providing a rail chair that embraces the confronting ends of the rails and prevent lateral displacement of one rail with relation to the 70 other, when a clamping member or strap 11 embraces the outer edges of the splice bars. Each splice bar has the inner side thereof provided with a longitudinal groove 12 providing clearance for the side plates 7. 75 The outer edge of each splice bar, contiguous to the ends thereof, is provided with vertical spike notches 13 and intermediate these notches the edge of the splice bar is cut away, to provide a tapering or wedge-shaped 80 portion 14. The splice bar, adjacent to this tapering or wedge-shaped portion 14, is provided with a raised tapering enlargement 15, said enlargement and the wedge-shaped portion 14 coöoperating to lock the clamping 85 member in engagement with the splice bars 9.

The inner sides of the clamping member 11 are tapered, as at 16, and prior to placing the rails in position, the splice bars 9 90 are placed in engagement with the clamping member 11. After the rails have been connected by the side plates 7 and properly positioned, the splice bars 9 are driven by a sledge or similar tool for driving the splice 95 bars 9 into positive engagement with the clamping member 11, and through the medium of the tapering enlargements 15, the clamping member 11 positively engages the splice bars or binds the same in engagement 100 with the rails. The enlargements 15 prevent the clamping member from sagging upon the outer edges of the splice bars, and after spikes 17 have been driven into notches 13 and into ties 4 to lock the splice bars, the 105 clamping member 11 will be firmly held intermediate the ends of the splice bars.

The invention has the following characteristics that provide a rail joint that can be used in connection with various types of 110 rails, either for sub-way or elevated structures. First, the splice bars serve function-

ally as fish-plates, and are held against the rails with such a grip that it is necessary to exert an enormous force on the rails to rupture the clamping member before the splice bars can be pulled out of their working position. Second, the clamping member stiffens the joint both horizontally and vertically at the juncture of the rails, thus providing a very stiff joint, as this additional material is in the best position for reinforcing the splice bars against lateral stresses and strains. Third, the rail joint consisting of but comparatively few parts, having no bolts, nuts or other small parts to become lost or broken, permits of the joint being manufactured at a small cost, and as no holes are to be drilled or punched after the rails have been positioned, ordinary labor can quickly install a joint.

20 I reserve the right to eliminate the side plates 7, and the openings 6, and to use the rail joint in connection with various kinds of ties or sleepers.

Having now described my invention, what 25 I claim as new, is;

1. In a rail joint, the combination with rails, pins arranged in the webs of said rails, and side plates provided with elongated openings to receive the ends of said 30 pins, of splice bars embracing said rails, said splice bars having integral tie plates for

supporting the base flanges of said rails, said splice bars having the outer edges thereof tapered, tapered enlargements carried by said splice bars adjacent to the tapered edges thereof, a clamping member adapted to embrace said splice bars, said member having the inner sides thereof tapered to engage the tapered edges of said splice bars while the upper inner edges of said member engage the enlargements and bind said splice bars upon said rails.

2. In a rail joint, the combination with rails, splice bars adapted to embrace the confronting ends of said rails, said splice bars having the outer edges thereof tapered, tapered enlargements carried by said splice bars adjacent to the tapered edges thereof, and a clamping member adapted to embrace said splice bars, said member having the inner edges thereof tapered to engage the tapering edges of said splice bars and bind said splice bars in engagement with said rails, while the upper inner edges of said member engage said enlargements and bind 55 said member relative to said splice bars.

In testimony whereof I affix my signature in the presence of two witnesses.

JOHN PIUS HEUER.
